[57] **CLAIM**

The ornamental design for a thread holder and minder,
as shown and described.

DESCRIPTION

FIG. 1 is a top, front, left side perspective view of a
thread holder and minder showing my new design;
FIG. 2 is a top, rear, right side perspective view thereof,
the sleeves on the dowels shown in an open position;
and

FIG. 3 is a bottom plan view thereof.

FIG 1

FIG 2

FIG 3
